UNITED STATES PATENT OFFICE.

OTTO ANDERSON, OF STILLWATER, AND ANDREW W. ANDERSON, OF LAKE ELMO, MINNESOTA.

PNEUMATIC ROCKER.

SPECIFICATION forming part of Letters Patent No. 637,065, dated November 14, 1899.

Application filed June 30, 1899. Serial No. 722,355. (No model.)

To all whom it may concern:

Be it known that we, OTTO ANDERSON, residing at Stillwater, and ANDREW W. ANDERSON, residing at Lake Elmo, in the county of Washington and State of Minnesota, citizens of the United States, have invented certain new and useful Improvements in Pneumatic Rockers; and we do hereby declare the following to be a full, clear, and exact description of the invention, such as will enable others skilled in the art to which it appertains to make and use the same.

Our invention is especially directed to a device for giving a resilient or cushioned action to rocking-chairs; and to this end it consists of the novel devices and combinations of devices hereinafter described, and defined in the claims.

The invention in its preferred form is illustrated in the accompanying drawings, wherein like characters indicate like parts throughout the several views.

Figure 1 is a side elevation, with some parts broken away, showing a rocker of a rocking-chair with our improved devices applied thereto. Fig. 2 is a view corresponding to Fig. 1, but showing the rocker in section. Fig. 3 is a bottom plan view of the said rocker, and Fig. 4 is a transverse section taken on the line $x^4 x^4$ of Fig. 1.

The rocker is indicated by the numeral 1, and portions of the chair-legs are indicated by the numeral 2. In its bottom or convex under surface or edge the rocker 1 is provided with a channel 3, which runs less than from end to end of said rocker and terminates in conical seats or extremities 4, as best illustrated in Fig. 2.

The channel or tube-seat 3 is formed in its sides with longitudinally-extended detent-grooves 5 for a purpose which will presently appear.

A pneumatic tube 6 is fitted into the tube-seat 3, so that it completes the under surface of the rocker and is adapted to sustain the weight of the chair and the occupant thereof. At its ends the tube 6 is formed conical or pointed, as indicated at 7, so that it fits the conical seats 4. On its sides, but considerably above its axis, the tube 6 is formed with longitudinally-extended detent-flanges 8,

which are adapted to fit into the detent-grooves 5 of the tube-seat 3 to coöperate with the seats 4 and tube ends 7 to hold the tube in working position when inflated.

55

At one end or at some other suitable point the tube 6 is provided with a charging-nipple or valve-stem 9, which projects through a suitable passage in the rocker, so that the tube or tire may be inflated by means of a pump suitable for the purpose—such, for example, as a bicycle-pump. When the tube is deflated, it may be readily applied with its ends 7 engaging the end seats 4 and its detent-flanges 8 engaging the coöperating grooves 65 5, and at such time it may also be readily removed from the rocker. When, however, the tire is thus placed in working position and inflated, it will be securely held in working position by the strain of the compressed and 70 confined air in the tube, which strain tends to lengthen the tube, as well as to hold the same round in cross-section.

A chair equipped with pneumatic tubes of the above character will have great resiliency, 75 and no jars would be produced in rocking, even though the chair is rocked upon a very irregular and rough floor or other supporting-surface. At its extreme ends the rocker is seldom used, and hence it is not necessary to 80 extend the pneumatic tube from end to end of the rocker; but, on the contrary, it is considered better construction for several reasons to terminate the tube short of the ends of said rocker. This leaves the rocker rigid 85 at its ends and protects the ends of the tube.

To prevent the rear ends of the rockers from scratching furniture and defacing walls we provide the same with rubber caps or covers 10, clearly shown in the drawings.

90

The pneumatic tube or tire above described, while especially adapted for application to rockers of rocking-chairs, is of course also adapted for application to other rockers—such as those of a cradle, for example—and it will 95 be understood that our invention above specifically described is capable of many modifications within the scope of the generic invention.

A chair of the above character will be much 100 appreciated by invalids and nervous persons.

It will also be understood that, if desired,

the rockers, instead of being made of wood, might be stamped or otherwise formed from pressed steel or other metal, channeled out to properly receive the tube.

5 What we claim, and desire to secure by Letters Patent of the United States, is as follows:

1. A rocker, provided in its under surface with a recess or groove 3 extending less than from end to end of said rocker and terminating in the conical end sockets 4, of the tube 6 pointed at its ends at 7, and engageable with said recess or seat 3, 4, and held in position when inflated, substantially as described.
2. A rocker formed in its under surface with 15 the longitudinal recess or seat 3 terminating

in the end sockets 4 and provided with the detent-grooves 5 in its sides, in combination with the pneumatic tube 6 terminating at its ends in the conical points 7 and provided at its sides with the detent-flanges 8, which tire 20 is held in position when inflated, substantially as described.

In testimony whereof we affix our signatures in presence of two witnesses.

OTTO ANDERSON.
ANDREW W. ANDERSON.
